UNITED STATES PATENT OFFICE.

ARTHUR F. BELLINGER, OF MOHAWK, NEW YORK.

TICKET-HOLDER.

1,134,988.

Specification of Letters Patent. Patented Apr. 13, 1915.

Application filed April 24, 1914. Serial No. 834,211.

To all whom it may concern:

Be it known that I, ARTHUR F. BELLINGER, a citizen of the United States, residing at Mohawk, in the county of Herkimer and State of New York, have invented certain new and useful Improvements in Ticket-Holders, of which the following is a specification.

This invention relates to new and useful improvements in ticket holders, and has for its principal object to provide a device which is adapted to be secured to the sides of cars between windows to hold tickets.

Another object of the invention is to provide a device which will hold tickets, price cards, checks, and similar devices to prevent the same from becoming displaced or lost.

A further object of the invention is to provide a simple and effective ticket holder which may be easily and cheaply constructed and which will be a material benefit to the traveling public, particularly where mileage is used and a receipt therefor is given by the conductor in charge of the train.

With these and other objects in view, the invention consists in the novel combination and arrangement of parts which will be fully set forth in the following specification and accompanying drawings, in which,

Figure 1 is a side view in elevation of a ticket holder constructed in accordance with this invention, Fig. 2 is an end view of the upper end thereof, Fig. 3 is a view of the opposite end, and Fig. 4 is a detail perspective view of the plate which is provided for holding the spring.

Referring now to the drawings by characters of reference, the numeral 1 designates the back of a car seat carrying a suitable block 2. The ticket holder is designated generally by the numeral 3, and is shown in position on the block. The ticket holder 3 above referred to, preferably comprises the plate 4 which is substantially hexagonal and is provided at one end with the loop 5, the use of which will appear as the description proceeds. Formed laterally of the plate 4 are the screw receiving apertures 6, by means of which the device may be secured in place. At the end of the plate 4 opposite the loop 5 is the upstanding post 7 having formed near its upper extremity a groove 8. The upper terminal of the post is preferably

spherical as at 9 and is arranged to hold the 55 coöperating member, which will be more fully hereinafter described, firmly in place. The coöperating member above referred to, is designated by the numeral 10 and is preferably a coil spring having one end reduced 60 as at 11 and provided with the loop 12 which is arranged to surround the post 7 and lie in the groove 8 as clearly illustrated in the drawings. The end of the spring opposite the looped end 12 is provided with the hook 65 member 13 which is arranged to extend through the aperture formed by the loop 5, and thus firmly hold the spring to the plate.

It will be apparent from the foregoing that in use, the plate 4 is secured in place 70 on the back of a seat at the desired point and the spring 10 placed thereon as illustrated in Fig. 1. In this position it will be apparent that the spring will be slightly expanded and when the conductor receives 75 the mileage from the person who is traveling, the receipt is placed between the coils of the spring as at 14, and thus it will be seen that the said receipt is held in such a way as to be visible and any disturbance of 80 the traveler is unnecessary.

While in the foregoing there has been shown and described the preferred embodiment of this invention, it is to be understood that such changes may be made in the combination and arrangement of parts as will fall within the spirit and scope of the invention as defined in the appended claim.

Having thus described my invention, I claim:

A ticket holder of the character described including a base plate, a coil spring secured to one end of the base plate, a reduced extension formed on the opposite end of the coil spring, a post carried by the opposite 95 end of the base plate, a loop on the reduced extension and arranged to surround the post to hold the coil spring slightly extended and in parallel relation with the base plate, the loop being arranged to be detached from the 100 post to give access to the base of the plate.

In testimony whereof I affix my signature in presence of two witnesses.

ARTHUR F. BELLINGER.

Witnesses:

C. L. PRINCE,
J. E. RAFTER.
